Primary Examiner — Mark Goodwin(74) *Attorney, Agent, or Firm* — Hamre, Schumann, Mueller & Larson, P.C.(57) **CLAIM**

The ornamental design for a mixing blade for a mixer for concrete, mortar, powders, dry or semi-dry granulates, mixtures with a cement base or similar or comparable mixtures, as shown and described.

DESCRIPTION

FIG. 1 is a perspective view of a mixing blade for a mixer for concrete, mortar, powders, dry or semi-dry granulates, mixtures with a cement base or similar or comparable mixtures showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.
